UNITED STATES PATENT OFFICE.

CHARLES W. CARR, OF MEADOW GROVE, NEBRASKA, ASSIGNOR OF ONE-HALF TO
HOLLIS B. CARR, OF MEADOW GROVE, NEBRASKA.

VALVE-SPRING LIFTER.

Application filed February 4, 1926. Serial No. 85,996.

The invention relates to improvements in devices for compressing the springs of engine valves, so that they may be entirely out of the way when removing the usual spring engaging means from the lower ends of the valve stems, incident to removal of the valves, for instance when valve grinding is to be done or when replacements are to be made.

10 The principal object of the invention is to provide a device of the character described which, while being rather simple and inexpensive, will be highly efficient and will possess a number of advantageous features.

15 With the foregoing in view, the invention resides in the novel subject matter herein-after described and claimed, the description being supplemented by the accompanying drawing.

20 Figure 1 is a perspective view of a spring lifter or compressor constructed in accordance with the invention.

Fig. 2 is an enlarged, fragmentary, vertical sectional view.

25 Fig. 3 is a detail vertical section through the free end of the valve holding arm, showing the relation of the valve holding finger with said arm.

30 Fig. 4 is a detail vertical sectional view through the spring engaging foot and associated parts, showing the manner of connecting said foot with a lower arm of the device.

In the drawing above briefly described, the numeral 5 designates a vertically disposed shank having downwardly facing ratchet teeth 6 on one edge. The lower end of this shank is provided with a T-head 7 which is received in the channel 8 of a channel-metal horizontal arm 9, the side flanges of said arm being formed with longitudinally spaced openings 10 through any of which a cotter pin or the like 11 may be passed, one end portion of the head 7 being formed with an opening through which this pin also passes. Thus, not only may the arm 9 be adjustably connected with the lower end of the shank 5, but said arm may be upwardly swung to an out-of-the-way position, when its use is not necessary and the tool is to be placed in a tool box or the like.

The bottom 12 of the channel metal arm 9, has a notch 13 formed in its free end, said notch receiving the upper end of a vertically elongated plate 14 whose rear edge abuts the inner wall of the notch. This plate 14 car-

ries a bifurcated foot 15 to straddle the lower end of a valve stem and engage the lower extremity of the valve spring. The rear end of this foot is formed with an upstanding leg portion 16 of channeled form, said leg portion receiving the body of the plate 14 and being connected detachably with the latter by means of a cotter pin or the like 17, passing through aligned openings in the leg and plate. The upper end of the plate 14 is riveted as at 18 to the side flanges of the arm 9. Engagement of the upper end of the leg 16, with the lower side of the arm 9, holds the plate 14 and the foot 15 against any pivotal action with respect to said arm.

70 The details just described permit the attachment of feet of different designs to the arm 9, according to the conditions encountered on different motors. Preferably, each foot 15 and its leg portion 16 are pressed 75 or drop-forged from a single body of metal, for ease in manufacture.

An upper, relatively large slide 19, and a lower, comparatively small slide 20, are mounted on the shank 5, said slides being 80 provided with upper and lower dogs 21 and 22 respectively, for coaction with the ratchet teeth 6. Preferably, a hand actuated yoke 23 is pivoted to the slide 20 for the purpose of holding its dog 22 released, when the two 85 slides and the shank must be rapidly adjusted, as when applying or removing the tool. A hand lever 24 is fulcrumed to the rear portion of the slide 19, as indicated at 90 25, the front end of said lever being preferably formed with two furcations 26 which straddle a portion of the slide, which portion may well have its sides cut away as at 27 to accommodate said furcations. Links 28 have their upper ends pivoted at 29 to 95 the furcations 26 while their lower ends are pivoted at 30 to the slide 20. By this arrangement, the slide 19 being held against descent as will hereinafter become apparent, upward movement of lever 24 forces the 100 links 28 and the slide 20 downwardly upon the shank 5, the dog 22 then clicking over the ratchet teeth 6 in readiness to operatively engage the last tooth over which it clicks. Then, depression of the lever 24, pulls up- 105 wardly upon the links 28 and slide 20, and the dog 22 then lifts the shank 5, causing upward movement of the arm 9 and foot 15, to compress the valve spring.

The front edge of the slide 19 is provided 110

with an integral, forwardly projecting lug 31 which extends into the channel 32 of an upper channel-metal arm 33, the side flanges of this arm being pivoted to said lug 31, as indicated at 34, so that the arm may be downwardly folded when not in use. Received in the channel 32, which channel opens downwardly, is a horizontally elongated head 35, said head being adjustably connected with the arm by a cotter pin or the like 36 passing through an opening in the head and adapted for engagement with any of longitudinally spaced openings 37 which are formed in the side flanges of said arm. The head 34 is provided, preferably at its front end, with an integral, downwardly projecting finger 38 of cylindrical form. The lower end of this finger is adapted to engage the valve whose spring is to be compressed, said lower end being preferably pointed as at 39. Threaded as at 40, upon this finger 38, above its pointed extremity 39, I prefer to employ a dome-like valve engaging member 41, so that both the point 30 and the member 41, or either of them, may be engaged with the valve, as occasion may demand. It will thus be seen that while the foot 15 is pulling upwardly upon the valve spring and the usual washer with which it is engaged, the valve is held against ascent, even should said washer bind to quite an extent upon the valve stem.

The device is rather simple and inexpensive, yet will be exceptionally desirable, its primary use being in garages or repair shops, in which the mechanics must be in readiness to effectively work upon machines of all makes. The device may be quickly and easily applied, easily operated to compress the valve springs, and quickly and easily disengaged from the motor after valve parts have been reassembled.

As excellent results are obtainable from the details disclosed, they are preferably followed. However, within the scope of the invention as claimed, variations may be made.

I claim:

1. In a valve spring compressor, a shank having a head at its lower end, a horizontal channel-metal arm whose channel receives said head, the front end of said arm having valve spring engaging means, and a pin for adjustably connecting said arm with said head, the side flanges of said arm having longitudinally spaced openings through any of which said pin may be inserted, permitting longitudinal adjustment of said arm, and valve engaging means carried by said shank for cooperation with said arm carried spring engaging means to hold the valve against ascent during the compression of the spring.

2. In a valve spring compressor, a shank, an arm carried by said shank and having a

downward projection at its front end, a valve spring engaging foot having an upstanding leg member at its rear end shaped to receive said downward projection, means for detachably connecting said leg portion with said projection, and valve engaging means carried by said shank for cooperation with said arm carried spring engaging means to hold the valve against ascent during the compression of the spring.

3. In a valve spring compressor, a shank, an arm carried by said shank and having a downward projection at its front end, a valve spring engaging foot having at its rear end an upstanding channel-shaped leg portion which snugly receives said projection and abuts the lower side of said arm, a pin passing through the side flanges of said leg portion and through said projection, and valve engaging means carried by said shank for cooperation with said arm carried spring engaging means to hold the valve against ascent during the compression of the spring.

4. In a valve spring compressor, a shank, a channel-shaped horizontal arm carried by said shank and having its bottom portion formed with a notch at its front extremity, a vertically elongated plate received at its upper end in said notch and between the side flanges of said arm, a fastener passing through said side flanges and the plate end, a valve-spring-engaging foot connected with said plate below said arm, and valve engaging means carried by said shank for cooperation with said arm carried spring engaging means.

5. In a valve spring compressor, a slide having an integral forwardly projecting lug, a channel-shaped horizontal arm whose rear end receives said lug, a fastener passing through the side flanges of said arm and through said lug, and valve engaging means at the front end of said arm, and valve spring engaging means to cooperate with said valve engaging means.

6. In a valve spring compressor, a channel-shaped arm whose channel opens downwardly, the side flanges of said channel being formed with longitudinally spaced openings, a head received in said channel, a pin insertible through said head and any of said openings, valve engaging means projecting downwardly from said head, and valve spring engaging means to cooperate with said valve engaging means.

7. A valve spring compressor including a vertically disposed finger whose lower end is adapted to contact with the center of a valve, and a dome-like valve-engaging member threaded on said finger, the peripheral edge of said dome-like member being concentric with said finger.

8. A valve spring compressor comprising a vertical shank having a horizontal for-

- wardly projecting arm at its lower end, said arm being provided at its front extremity with a valve-spring-engaging-foot, upper and lower slides upon the shank, a forwardly projecting horizontal arm carried by the upper slide and provided at its front extremity with downwardly projecting valve-engaging means, a lever fulcrumed on the upper slide and linked to the lower slide, and co-acting means on the shank and the two slides for permitting upward movement of the shank through the upper slide and downward movement of the lower slide upon the shank.
- 15 9. A valve spring compressor comprising
- a shank whose lower end is provided with a forwardly projecting arm having valve spring engaging means, a pivotal connection between said arm and said shank permitting upward swinging of the arm when its use is not desired, a slide upon the shank having a forwardly projecting valve-engaging arm, a pivotal connection between this arm and the slide permitting downward swinging of the arm when desired, and means for relatively adjusting the slide and shank. 20 25

In testimony whereof I have hereunto affixed my signature.

CHARLES W. CARR.
